RESISTANCE

Marcus W. Weiscope, Philadelphia, Pa., assignor
to International Resistance Company of Phila-
delphia, Pa., a corporation of Delaware

Application December 26, 1930, Serial No. 504,847

12 Claims. (Cl. 201—63)

The invention relates to resistors and mountings therefor.

One of the objects of the invention is to provide a mounting for a plurality of resistors so constituted that any resistor may be readily removed and replaced with a different resistor. Another object of the invention is to provide a mounting for a resistor by means of which it may be readily attached to one or more other resistors. Another object of the invention is to provide a mounting for resistors whereby resistors of varying sizes and characteristics may be readily connected together in gang formation. Another object of the invention is to provide a mounting for resistors which is durable and which may be manufactured at low cost. Another object of the invention is to provide a method of mounting a resistor which is simple and very practical. Other objects will be in part obvious or in part pointed out hereinafter.

The invention accordingly consists in the features of construction, combinations of elements, arrangements of parts and in the several steps to and relation and order of each of said steps to one or more of the others thereof, all as will be illustratively described herein, and the scope of the application of which will be indicated in the following claims.

30 In referring to the drawing, the terms "plan", "side", "underside", and the like, are used simply to facilitate the description, as the resistor gang of the invention may be attached to any suitable apparatus in any desired position. In the accompanying drawing, in which is shown one of various possible embodiments of the mechanical features of this invention.

Figure 1 is a view of the underside of a single resistor and its holding block,

40 Figure 2 is a longitudinal sectional view of the resistor and holding block taken on the line 2—2 of Figure 1,

Figure 3 is an isometric view of the resistor and holding block,

45 Figure 4 is a plan of a gang of resistors and their holding blocks connected together,

Figure 5 is an underside view of the gang, and

Figure 6 is a view partly in side elevation and partly in section of the gang.

50 Similar reference characters refer to similar parts throughout the several views of the drawing.

Referring to all the figures, but more particularly to Figure 2, the resistor, indicated generally by the numeral 10, preferably consists of

a rod or bar of porcelain or other insulating substance 11 having a capillary passage 12 through which extends a resistance conductor 13 embedded in metal end pieces 14, 14. The resistance conductor 13 preferably comprises a glass rod or filament covered with a conductive coating of high resistance material, such as carbon. The conductor 13 is in intimate contact with the wall of the capillary passage 12, the diameter of the conductor being preferably as near to the 10 diameter of the capillary passage 12 as is practicable. The porcelain insulator 11 is a good dielectric, so that there is no leakage of current through it, but as it readily conducts heat, any heat generated by the resistance element 13 is 15 quickly dissipated.

The metal end pieces 14, 14 are rigidly connected to the porcelain insulator rod 11. This may be done by relating the rod and the projecting ends of the resistance conductor 13, 20 which is supported by the rod 11, to a suitable mold and molding the metal end pieces 14, 14 on said insulator rod 11, thereby completely embedding the resistance conductor 13, as is clearly shown in Figure 2. Preferably the metal end pieces 14, 14 are of readily moldable metal, such as type metal, which in cooling expands in the mold and firmly grips the ends of the porcelain rod 11 so as to form a firm and rigid body. 25

Referring more particularly to Figures 1, 2 30 and 3, firmly embedded in each molded metal end piece 14 is a conductor 15 which desirably is a flexible metal wire. As shown in Figure 2, a substantial length of each conductor 15 is contained in a metal end piece 14, the conductor being related to the mold at the time that the metal end pieces are molded to secure a perfect electrical and mechanical connection. The two conductors 15 of each resistor are electrically connected by the resistance conductor 13, and the union is "noiseless" in any audio circuit. 35

Still referring to Figures 1, 2 and 3, on the rod 11 between the molded end pieces 14, 14 is a holding block 16. In accordance with certain features of this invention the block 16 is 40 molded upon the rod 11 at the same time that the metal end pieces 14, 14 are molded upon the rod 11, a single mold being provided to form the end pieces 14, 14 and the block 16, the cavities of the mold being joined by suitable gates. The end pieces 14, 14 and the block 16 may be thus molded at a single operation, thus reducing the cost of manufacture of the unit of Figures 1, 2 and 3 to a very low amount. Assuming that the molded end pieces 14, 14 were 45 50

of type metal, when the holding block 16 is made in the same mold in which the end pieces 14, 14 are made, the holding block 16 will also be of type metal which, as noted above, expands in the mold upon cooling, and therefore the block 16 firmly grips the porcelain insulator rod 11. It should be understood, however, that so far as certain features of this invention are concerned, the holding block 16 might 10 be made in other ways, or molded of other material.

Referring more particularly to Figures 1 and 3, the holding block 16 has a pair of opposite sides 17 and 18 which are in planes parallel 15 to each other and to the axis of the resistor 10. In one of these sides, for example in the side 17, and preferably substantially above the axis of the resistor 10, as is better shown in Figure 3, is an indenture 19. As is better shown in Figure 1, in the side 18 and opposite the indenture 19 is a tenon 20. The tenon 20 is complementary to the indenture 19 and, as shown, both the tenon and the indenture are hemispherical in shape.

Still referring to Figures 1 and 3, extending away from the body of the holding block 16 are a pair of parallel legs 21, 21 which define between them a space 22 through which may extend a member parallel to the resistor 10. The legs 21, 21 together with the body of the block 16 make the complete holding block 16 U-shaped. The holding block 16 has a hole 23 through it in which is contained the porcelain insulator rod 11, and the axis of the hole 23 is perpendicular to the plane of the sides of 35 the space 22.

Referring now to Figures 4, 5 and 6, any desired number of holding blocks 16 may be readily joined together. As shown in these 40 figures, the flat side 17 of one holding block abuts the flat side 18 of the next holding block, and the tenon 20 of one holding block fits in the indenture 19 of the adjacent holding block. Owing to the relationship between the sides 17 and 18 of the several holding blocks 16, the 45 axes of the several holes 23 in the several holding blocks 16 are in parallel planes, while the interfitting of the tenons 20 and indentures 19 causes alignment of the several holding blocks 16 along the axes of the indentures and tenons 19 and 20.

Referring now particularly to Figures 5 and 6, a rod 25 is located in the space 22 between the legs 21, 21 of the several holding blocks 16, thus aligning all the right-hand legs and all 50 the left-hand legs respectively of the several holding blocks 16. The several spaces 22 thus merge to form a channel, and preferably the rod 25 has a diameter substantially the same as the width of this channel so that lateral 55 movement of one holding block with respect to another is prevented. The rod 25 is threaded at each end and nuts 26, 26 are provided to force the several holding blocks 16 together, thus forming a compact and rigid device. In 60 Figure 6 several of the holding blocks are shown in section to show the interlocking of the tenons 20 and indentures 19, and the tenons and indentures effectively prevent sliding movement of one holding block 16 with respect to another, while the rod 25 and the nuts 26 hold the holding blocks together and the rod 25, by reason 65 of the fact that it is in substantial contact with each leg 21 of every holding block 16, prevents torsional movement of the entire unit. For the 70

purpose of attaching the assembled unit in any desired apparatus, L-shaped brackets 27, 27 are desirably provided, each bracket having a hole 28 through which the rod 25 passes, and a hole 29 for the passage of an attaching screw 5 or the like.

Referring now particularly to Figures 4 and 6, with the holding blocks 16 fastened together as described, the axes of the several resistors are parallel. The length of each holding block 10 16 (and by length is meant that dimension perpendicular to the axis of the resistor 10 and parallel to the rod 25) is greater than the diameter of the metal end pieces 14, 14 by a substantial amount, so that the metal end pieces 14 of 15 successive resistors 10 do not touch each other.

Referring now particularly to Figure 4, some of the holding blocks 16 contain resistors 10 of the general dimensions shown in Figures 1, 2 and 3, but there is also shown in this figure 20 a resistor 10a whose insulator rod 11a is of larger diameter than an insulator rod 11. In Figure 4 is also shown a resistor 10b whose insulator rod 11b is of smaller diameter than a rod 11. A given gang assembly of resistors may 25 include resistances 13 of greatly differing resistance values, and likewise it may be desirable to include in a given gang resistors of widely different current capacities. As resistors of large 30 current capacity require insulator rods of large 35 diameter, it is highly desirable to be able to join together in a gang resistors of different sizes. The length of the blocks 16 is greater than the diameter of the metal end pieces 14a, 14a on the ends of the insulator rods 11a, 11a 35 of the large sized resistors 10a, and thus there is no danger of contact between adjacent metal end pieces 14 of adjacent resistors.

If for any reason it becomes desirable to replace a resistor 10 with another resistor, either 40 because a different resistance value is desired in the gang at that point or because of failure of a particular resistor, the gang may be readily disassembled by removing the nuts 26, and the old resistor 10, with its holding block 16, replaced by a different one. The ease with which 45 a particular unit in the gang may be replaced, coupled with the rigidity of the unit when assembled, is a very important feature of the invention. There is practically no stress upon the 50 individual holding block 16 except a compressive force, and so there is no tendency of a resistor 10 to turn or move endwise in the hole 23.

By the method of manufacture described, resistors and their holding blocks 16 cost very little 55 more than resistors alone, and since the remaining parts of a gang may be made at very small cost, an entire gang of resistors costs little 60 more than the resistors themselves. At the same time the gang as such is very durable and may be composed of any number of resistors desired, simply by providing a longer or shorter rod 25.

It will thus be seen that there has been provided 65 by this invention a method and apparatus in which the various objects hereinabove set forth, together with many thoroughly practical advantages, are successfully achieved.

As various possible embodiments might be 70 made of the mechanical features of the above invention and as the art herein described might be varied in various parts, all without departing from the scope of the invention, it is to be understood that all matter herein set forth, or

shown in the accompanying drawing, is to be interpreted as illustrative and not in a limiting sense.

I claim:

5. 1. In apparatus of the class described, the combination with a plurality of resistors each of which comprises an elongated body of insulating material, a resistance conductor in said body, molded metal end caps on the ends of said body, and conductors embedded in said molded metal end caps, of an individual holding block of the same metal as said end caps for each resistor molded on the elongated body and having a pair of spaced legs, a tenon, and an indenture, a rod fitting between the several pairs of legs, one or more nuts on the ends of said rod, and holding brackets secured to the apparatus by said rod. 5
10. 2. A resistor gang construction comprising a plurality of resistors, individual holding means for each resistor comprising a member permanently affixed to such resistor and contacting no other resistor, a pair of projecting portions formed on each individual holding means, a connecting member fitting between said several pairs of projecting portions to hold said several holding means together, and aligning means to align said individual holding means. 10
15. 3. A resistor gang construction comprising a plurality of resistors, individual holding means for each resistor comprising a member permanently affixed to such resistor and contacting no other resistor, a pair of projecting portions formed on each individual holding means, and a connecting member fitting between said several pairs of projecting portions to hold said several holding means together. 15
20. 4. A resistor gang construction comprising a plurality of resistors having elongated body portions, individual holding means for holding each resistor at an intermediate point on the body portion, means to hold together said several holding means, and interlocking means to prevent relative lateral or torsional movement of the several individual holding means. 20
25. 5. A resistor gang construction comprising a plurality of resistors having elongated body portions, individual holding means for holding each resistor at an intermediate point on the body portion, and means to hold together said several holding means. 25
30. 6. A resistor gang construction comprising a plurality of rod-like resistors, a separate holding member for each resistor having a pair of 30
35. projecting portions extending away from the resistors each holding member being formed to hold its resistor by at least partial circumferential contact therewith, and a rod fitting between said several pairs of projecting portions to hold said holding members and therefore said resistors together. 35
40. 7. A resistor gang construction comprising a plurality of rod-like resistors, a separate holding member for each resistor each holding member being formed to hold its resistor by at least partial circumferential contact therewith, and a rod connecting said holding members together. 10
45. 8. A resistor gang construction comprising a plurality of rod-like non-inductive resistors, a separate individually gripping holding member for each resistor comprising a member permanently affixed to such resistor and contacting no other resistor, and tenon and indenture means provided by said holding members. 15
50. 9. A resistor unit comprising an elongated resistor body, a U-shaped member gripping said body, a tenon at one end of said member, and an indenture at the other end of said member, the plane of the U being parallel to the elongated body, and the legs of the U being perpendicular to the elongated body. 20
55. 10. A holding block for a resistor comprising a member having a pair of legs between which is adapted to be received a member to hold said block, said block having a transverse aperture to receive a resistor, i. e. the aperture for the resistor being transverse to the member which holds the blocks together, a tenon at one end of said block, and an indenture at the other end of 30
60. said block. 35
65. 11. A holding block for a resistor comprising a member having a pair of legs between which is adapted to be received a member to hold said block, said block having a transverse aperture 40
70. to receive a resistor, i. e. the aperture for the resistor being transverse to the member which holds the block. 45
75. 12. A resistor unit comprising an elongated body of insulating material, a resistance conductor in said body, molded metal end caps on the ends of said body, and a molded block embedding and gripping said body between said end caps, said block defining an aperture for the reception of a member to hold a plurality of the units together, the axis of said aperture being substantially at right angles to the longitudinal axis of said body. 50
